UNITED STATES PATENT OFFICE

JAMES A. SMITH, OF MINNEAPOLIS, MINNESOTA

DESIGN FOR AN AUTOMOBILE

Application filed January 20, 1932. Serial No. 42,562. Term of patent 7 years.

To all whom it may concern:

Be it known that I, JAMES A. SMITH, a citizen of the United States, residing at Minneapolis, in the county of Hennepin and State of Minnesota, have invented a new, original, and ornamental Design for an Automobile, of which the following is a specification, reference being had to the accompanying drawings, forming part thereof.

Fig. 1 is a perspective view of the auto-

mobile as seen from the front of the left side; Fig. 2 is a perspective view as seen from the side of the automobile;

Fig. 3 is a top plan view of the automobile; and

Fig. 4 is a front view of the automobile.

I claim:

The ornamental design for an automobile, as shown.

JAS. A. SMITH.
